UNITED STATES PATENT OFFICE.

HARRY H. PUGH, OF TOPEKA, KANSAS.

SILO AND TANK CONSTRUCTION.

1,171,881.

Specification of Letters Patent. Patented Feb. 15, 1916.

Application filed February 27, 1915. Serial No. 10,945.

To all whom it may concern:

Be it known that I, HARRY H. PUGH, a citizen of the United States, residing at Topeka, in the county of Shawnee and State of Kansas, have invented certain new and useful Improvements in Silo and Tank Construction, of which the following is a specification.

My invention relates to the construction 10 of silos and tanks made of vertically disposed planks or staves.

It relates to the construction of the main body of the structure and not to the vertical opening or series of openings provided in 15 silos for the filling and emptying thereof.

It has been a practice heretofore to build such structures of wood planks or staves which have tongue-and-groove connections along their contiguous edges, with numerous metal bands surrounding the structure 20 to hold the staves together. To facilitate the assembling of the parts in the erection of the structure and to insure its durability, it has been necessary to use quite wide staves, 25 say six inches or more, of clear lumber; also it has been found necessary that long timbers be used in order to avoid horizontal seams or joints. Inasmuch as the timbers of the larger dimensions are more costly proportionately than timbers or lumber of 30 smaller dimensions, these requirements have made for increased cost of the silos and tanks.

It is the object of my invention to utilize 35 the lumber of smaller dimensions, *i. e.*, to provide such a system of construction that narrower staves may be used and also that short lengths may be used and safely spliced wherever a horizontal joint may be; also to 40 avoid the necessity of the hoops or bands, except possibly as supplementary factors of safety, by connecting the contiguous staves so the structure will be self-supporting.

My invention comprises an arrangement 45 of vertically disposed staves with tongue-and-groove connections, or spline-and-groove connections, together with spikes running through the studs horizontally and driven into the contiguous staves; also it 50 comprises a method of securing together contiguous staves and splines by means of spikes; and it also comprises the parts, improvements and combinations hereinafter set forth and claimed.

In the drawings accompanying and forming 55 part of this specification and in the de-

scription of the drawings, I have shown my invention in its preferred form and what I deem to be the best mode of applying the principles thereof; but it is to be understood that within the scope of the appended 60 claims I contemplate changes in form, proportions, and materials, the transposition of parts, and the substitution of equivalent members, without departing from the spirit 65 of my invention.

Figure 1 is a sectional plan view on a plane indicated by the line 1 in Fig. 2. Fig. 2 is an outside elevation, part being shown in section. Fig. 3 is a vertical section 70 through the wall, on a plane indicated approximately by the line 3 in Fig. 2, showing the horizontal joint.

Similar reference characters indicate like or corresponding parts throughout the several views.

The vertically disposed staves or timbers 4, 5, 5 are formed with grooves 6, 6, 6 in their vertical edges and these grooves register with each other. Each stave except the first is also formed with a series of horizontal holes 7, 7 passing through from groove to groove. In the manner of assembling hereinafter explained no such holes are necessary in the stave 4. As noted in Fig. 1, 85 the edges of the staves are slightly beveled to correspond with the radius of the silo or tank to be constructed, so that the parts will be easily assembled into a circular wall. The splines or loose tongues 8, 8, 8 are placed in 90 contiguous grooves, as shown in the drawings, to hold the staves in alinement and form a seal, and the sealing is perfected by the use of a suitable cementing material, such as a suitable wood preserver, creosote 95 or asphalt preparation, of proper consistency applied to the joining portions immediately before assembling so that the parts may be pressed firmly together while the cementing material is soft. The cementing 100 material is indicated by the numeral 11, and renders the joint impervious to moisture and air. While I prefer to use the loose tongue and the two grooves, it will also be understood that under some circumstances, any 105 other form of tongue-and-groove connection may be used as an equivalent.

To assemble the structure, I prefer to start with the stave 4 and build both ways therefrom. The contiguous staves are connected 110 to the stave 4 with the splines 8, 8 in proper position and with the cementing material

applied. Then a spike is placed in each hole 7 of the staves 5, 5, and driven through the splines and into the stave 4. Then the next staves are similarly assembled and spiked to those so fastened, and this is continued to complete the wall to the vertical opening or series of openings with which this invention is not concerned. Obviously one might commence by placing the stave 4 at one side 10 of the opening and then continuing around to the other side of the opening; but the suggested plan is quicker. Obviously, too, in the construction of round tanks without the vertical opening, devices are necessary 15 for connecting the staves filling the final gap. The heads of the spikes are driven into the wood with the effect of countersinking them into the bottom of the groove so as not to interfere with the spline next to 20 be applied.

The holes 7, 7, which are previously prepared for the reception of the shanks of the spikes are useful for two very important reasons, namely: They positively eliminate the 25 danger of splitting the stave through which the spike is first extended; and they serve as a positive guide to guide the spike straight. In addition they lessen the labor in the actual erection of the silo. And by driving the 30 spike through the spline, a slight expansion of adjacent portions of the spline is caused, resulting in more firm pressure of the sides of the spline against contiguous sides of the grooves, thus making a stronger joint.

35 A horizontal joint may be easily and safely made by means of a similar cemented horizontal spline 10.

It is, of course, acknowledged that the spline-and-groove connection would hardly suffice to hold the staves together against the outward pressure of the contents of the structure; but, instead of using hoops or bands for this purpose, I use the spikes.

I contemplate using standard or ordinary 45 two-by-four inch lumber, thereby effecting a great saving per unit of lumber over those structures using lumber of the larger dimensions. Preferably, too, the staves are to be planed, grooved, beveled, and drilled at a factory previous to shipping. It thus becomes 50 a comparatively simple task to erect the structure with the use of only the simplest tools. Also, by the use of the narrower staves, it becomes a simple matter to secure them 55 together by means of spikes, whereas this would scarcely be practicable with the wider timbers. It is preferred to drill the holes for the head-end of the spikes for the reasons that the holes can be properly drilled 60 at properly spaced points, the danger of splitting the stave is avoided, considerable labor is saved the person erecting the structure, it insures the proper number of spikes being properly used, and enables the shipper 65 to determine accurately the amount of metal

required. It is understood that the point of the spike is to be driven through the spline or tongue and into the contiguous stave.

Having thus described my invention, what I claim as new and desire to secure by Letters Patent is:

1. In silos, tanks, and similar structures, the combination of vertically disposed staves placed edge to edge, the contiguous vertical edges being formed with registering grooves 75 and being beveled according to the radius of the structure and each stave except the first being formed with horizontal holes extending through its body from groove to groove, a cementing material for sealing the joints, 80 splines for contiguous grooves, and spikes extending through said holes and driven through the contiguous splines and into the contiguous staves, the heads of the spikes being countersunk. 85

2. In silos, tanks, and similar structures, the combination of vertically disposed staves placed edge to edge the contiguous edges being formed with registering grooves and said staves except the first being formed with 90 horizontal holes extending through their bodies from groove to groove, splines for contiguous grooves, and spikes extending through the holes in each stave and driven through the contiguous spline and into the 95 contiguous stave.

3. In tanks, silos, and similar structures, the combination of staves placed edge to edge the contiguous edges being formed with registering grooves and one of each contiguous 100 pair of said staves being formed with transverse holes extending through their bodies from groove to groove, splines for the contiguous grooves, and spikes extending through the holes in one of each contiguous 105 pair of staves and driven into the contiguous stave.

4. In silos, tanks, and similar structures, the combination of two contiguous staves formed with grooves along their contiguous 110 edges and one of said staves having transverse holes extending through its body and terminating in its grooves, a spline fitting in said grooves, and spikes extending through said holes and driven through said spline 115 and into the adjacent stave.

5. In silos, tanks, and similar structures, the combination of contiguous staves placed edge to edge and formed with spline-and-groove connections along their contiguous 120 edges, one of the staves in each contiguous pair of staves being formed with prepared holes extending through the body of the stave edgewise, and spikes having their shanks fitting in said holes and driven 125 through the contiguous spline and into the contiguous stave.

6. In silos, tanks, and similar structures, the combination of contiguous staves placed edge to edge and formed with spline-and- 130

groove connections along their contiguous edges, one of the staves in each contiguous pair of staves being formed with prepared holes extending edgewise through its body, and spikes having their shanks fitting in said holes and driven into the contiguous stave.

In testimony whereof I have affixed my signature in presence of two witnesses.
